A CORPORATION OF CONNECTICUT

OIL BURNER

Application filed July 17, 1931. Serial No. 551,514.

This invention relates to means for electrically igniting the fuel of oil burners of the type provided for stoves or ranges, that have metallic bases which are surmounted by perforated cylindrical shells, the bases having annular grooves containing wicks with openings between the wick grooves for the upward flow of air for supporting combustion and having a central intake for the admission of oil, with passages leading therefrom to the wick grooves. It is somewhat difficult to light such burners as they have been previously constructed on account of the inaccessibility of the wicks and owing to the fact that the oil, being liquid when first admitted and before the parts have become heated sufficiently to vaporize the oil, does not light readily.

The object of this invention is to so construct and arrange the ignition elements and the wick that the fuel may be very quickly and easily ignited.

This object is attained by forming the bodies of the wicks of braided or woven strands of non-inflammable material, such as fibrous asbestos, and incorporating therewith metallic wires in such manner that they will hold the fire-resisting material together and keep the wicks in shape and at the same time will provide electric conductors having considerable resistance, and locating the terminals of a high-tension electrical circuit adjacent to the wicks in such positions that when the current is turned on it will jump from the terminals to the wires and cause such heat that the liquid fuel with which the wicks are saturated is instantly converted into gas and the required flame will result.

In the accompanying drawing, Fig. 1 is a plan of a double oil burner of the type referred to, provided with the improved ignition means, the perforated shells and cover pieces being removed from one burner and the electrical circuit being illustrated in diagram. Fig. 2 is a vertical section taken on the plane indicated by the dotted line, 2-2, on Fig. 1. Fig. 3 illustrates in detail, on greatly enlarged scale, a portion of one composite wick and an electrical terminal adjacent to its upper edge.

The bases, 1, of the burner shown are connected by bars, 2, the center bar being utilized for the connection of a support. Each of the bases has a central pocket, 3, opening into the middle of which is a fuel intake pipe, 4. Surrounding the central pocket are annular grooves, 5 and 6, in which are located wicks, 7 and 8. Passages, 9, are made from the central pocket to the inner groove, 5, and passages, 10, are made from the inner groove, 5, to the outer groove, 6. A plate, 11, may be loosely placed over the central pocket. Supported by the walls of the grooves are four concentric perforated cylindrical shells, 12, and resting on the top of the shells are a cover plate, 13, and a cover ring, 14. There are openings, 15, through the bases inside of the inner shell, and openings, 16, through the bases between the intermediate shells.

The wicks, 7 and 8, preferably have a body of woven strands, 17, of asbestos or the like non-inflammable substance, incorporated with which are conducting wires, 18. Attached to the outer rims of the bases are insulating blocks, 19, through which pass circuit wires, 20. In the openings 16, between the inner and outer wick grooves are similar insulating blocks, 21, with circuit wires, 22. It is preferred to arrange these insulating blocks, which are both heat and electric insulators, so that the upper terminals of the wires, 20 and 22, will be opposite the passages from the central pocket to the inner wick groove and from the inner wick groove to the outer wick groove, as shown in Fig. 1; and it is desirable to have the circuit wire terminals adjacent to the upper edges of the wicks. These circuit wires are connected with fixed terminals, 23, of a switch, 24, that controls circuit from a spark coil, 25, and battery, 26, which is grounded at 27. The wick conducting wires, 18, are grounded upon the bottom or sides of the base of the burner.

When the switch blade is thrown into engagement with one of the switch terminals, a circuit is established from the spark coil to a circuit terminal adjacent to the wick, and the current jumping from the terminal to the wick wires produces a hot spark which,

together with the heating of the wick wires, immediately gasifies the liquid oil so that the fuel ignites quickly. It has been found that when the circuit terminals are located 5 opposite the passages to the wick grooves there is more air than there would be if the terminals were not opposite the passages, and the fuel lights almost at once, and it is desirable to have the circuit terminals slightly 10 higher than the upper edges of the wicks.

With this construction, the conducting wires in the wicks not only hold together the fibrous heat-resisting material of the body of the wicks, but also form heat-generating 15 conductors which readily conduct the current and so add their heat as to cause a rapid volatilization of the fuel oil.

The invention claimed is:

1. An oil burner comprising a metallic base 20 provided with a central pocket and two concentric grooves, with a fuel intake opening to said pocket and fuel passages from the pocket to the inner groove and from the inner to the outer groove, wicks comprised of woven asbestos fibers and grounded electrical resistance wires, located in said grooves, insulators fixed to the base, circuit wires passing through said insulators and terminating, one adjacent to the wire of the inner wick and the other adjacent to the wire of the outer wick, and high tension current producing means connected with the circuit wires.

2. An oil burner comprising a metallic base 25 provided with a central pocket and two concentric grooves, with a fuel intake opening to said pocket and fuel passages from the pocket to the inner groove and from the inner to the outer groove, wicks comprised of woven asbestos fibers and grounded electrical 30 resistance wires located in said groove, insulators fixed to the base, circuit wires passing through said insulators and terminating, one adjacent to the wire of the inner wick opposite a fuel passage to the inner groove and the other adjacent to the wire of the outer wick opposite the fuel passage to the outer groove, and high tension current producing 35 means connected with the circuit wires.

3. An oil burner comprising a metallic base provided with a central pocket and two concentric grooves, with a fuel intake opening to said pocket and fuel passages from the pocket to the inner groove and from the inner to the outer groove, wicks comprised of woven asbestos fibers and grounded electrical 40 resistance wires located in said grooves, insulators fixed to the base, circuit wires passing through said insulators and terminating, one adjacent to the wire of the inner wick opposite a fuel passage to the inner groove and the other adjacent to the wire of the outer wick opposite the fuel passage to the outer groove, high tension current producing 45 means connected with the circuit wires.

wires, and switching means for directing current to the different circuit wires.

4. An oil burner comprising a base having a fuel groove in its upper surface and means for admitting fuel to said groove, perforated 70 tubular walls supported by said base and forming a combustion chamber above said groove, a fuel absorbent wick comprised of fire resisting fibers and electrical conducting wires located in said groove, said wires being 75 grounded through the base, an insulator with an end extending through a shell into the combustion chamber, a circuit wire passing through said insulator and terminating adjacent to said wick, and high tension current 80 producing means connected to said circuit wire whereby when the high tension current is turned on it will jump from the terminal of said circuit wire to the wires in the wick.

5. An oil burner comprising a base having a fuel groove in its upper surface and means for admitting fuel to said groove, spaced tubular walls supported by said base and forming a combustion chamber above said groove, a fuel absorbent wick comprised of fire resisting fibers and electrical conducting wires 85 located in said groove below said combustion chamber, said wires being grounded through the base, an insulated circuit wire passing through a shell and terminating adjacent to 90 said wick, and high tension current producing means connected to said circuit wire, whereby when the high tension current is turned on it will jump from the terminal of said circuit wire to the wires in the wick 95 and ignite the fuel contained therein.

6. An oil burner comprising a base having concentric fuel grooves in its upper surface and means for admitting fuel to said grooves, perforated tubular walls supported by said 105 base and forming concentric combustion chambers above said grooves, fuel absorbent wicks comprised of fire resisting fibers and electrical conducting wires located in said grooves, said wires being grounded through 110 the base, insulators with ends extending through the shells into the combustion chambers, circuit wires passing through said insulators and terminating adjacent to said wicks, high tension current producing 115 means connected to said circuit wires, and means for directing the high tension current to said circuit wires.

7. An oil burner comprising a base having a fuel groove in its upper surface, means for admitting fuel to said groove, and air openings through the base inside of said groove, perforated tubular walls supported by said base and forming a combustion chamber above said groove and outside of said air 120 openings, a fuel absorbing wick comprised of fire resisting fibers and electrical conducting wires located in said groove, said wires being grounded through the base, an insulator with an end extending through a shell 125

into the combustion chamber, a circuit wire passing through said insulator and terminating adjacent to said wick, and high tension current producing means connected to said 5 circuit wire.
